UNITED STATES PATENT OFFICE.

SIMEON J. HICKS, OF ENGLEWOOD, ILLINOIS.

MORTISING-TOOL.

SPECIFICATION forming part of Letters Patent No. 502,120, dated July 25, 1893.

Application filed May 21, 1892. Serial No. 433,838. (No model.)

To all whom it may concern:

Be it known that I, SIMEON J. HICKS, of Englewood, in the county of Cook and State of Illinois, have invented a new and Improved 5 Mortising-Tool, of which the following is a full, clear, and exact description.

The object of the invention is to provide a new and improved mortising tool, which is simple and durable in construction, and arranged 10 to quickly and conveniently form a complete square or rectangular mortise without much danger of breaking the bits or chisel.

The invention consists of certain parts and details, as will be fully described hereinafter 15 and then pointed out in the claims.

Reference is to be had to the accompanying drawings, forming a part of this specification, in which similar letters of reference indicate corresponding parts in all the figures.

20 Figure 1 is a side elevation of the improvement with parts in section. Fig. 2 is an inverted plan view of the chisel; and Fig. 3 is a sectional plan view of the gearing for the bits, on the line 3—3 of Fig. 1.

25 The improved mortising tool is provided with the head A, having a reciprocating motion and mounted to slide in suitable guideways B, arranged on the usual mortising machine. On the lower end of the head A is secured 30 the chisel C, made hollow and having the lower edges of the sides and ends sharpened so as to readily cut into the wood to form a square or rectangular mortise. A series of transversely extending bars D, connect 35 the sides of the hollow chisel with each other, the said bars being chamfered at both sides to form a cutting edge to extend in line with the cutting edges of the sides and ends of the chisel. The bars also form circular 40 openings E, for the passage of the shanks of the bits F, extending with their cutting ends a short distance below the chisel C, see Fig. 1. The upper ends of the bits F are secured 45 in elongated gear wheels G, mounted to turn in suitable bearings arranged in the head A, the several gear wheels being in mesh with one another, as is plainly shown in Figs. 1 and 3, so that when one of the said gear wheels is rotated all the gear wheels rotate in unison. It will be seen that the adjacent 50 gear wheels rotate in opposite directions, and consequently the bits F held on the corre-

sponding gear wheels are made right and left handed according to the direction in which the gear wheels turn, so that all the bits cut 55 at the same time when the gear wheels are rotated. As shown in Fig. 1, the two outermost gear wheels G receive a rotary motion in opposite directions, the said gear wheels being, for this purpose, provided on their upwardly extending shafts with pulleys H, connected by belts with suitable machinery for imparting a rotary motion in opposite directions to the said outermost gear wheels. Now, it will be seen that when the head A is fed 60 downward upon the wood, and the bits F are revolved as before described, then the bits cut into the wood in advance of the chisel, which latter, on following, cuts by its sharp sides and ends, as well as the transverse cutting bars D, the remaining portion of the wood not cut by the bits, so that the entire mortise 65 is formed. It is understood that the chips are confined only to the twist in the lower part of the bit for a very short time, that is, 70 until they pass the upper edge of the cutting bars D; as then the chips are free to pass from the twists into the space formed above the bars in the hollow chisel, and consequently 75 tight packing and clogging up of the bits are 80 prevented. It will further be seen that as the lower ends of the bits are guided in the lower part of the hollow chisel C, the said bits are not liable to break, owing to the bearing 85 they have in the chisel, and also in consequence of the removal of the surplus stock by the cutting edges of the chisel and the bars D. Thus it will be seen that the bits do not clog up with chips, and consequently the 90 said bits are not prevented from revolving 95 freely, and as all the bits revolve simultaneously it would be very dangerous in case one of the bits should be clogged up as all the others would be affected, on account of the several bits being positively geared together.

Having thus fully described my invention, I claim as new and desire to secure by Letters Patent—

1. In a mortising tool, a hollow chisel provided at its cutting end with cutting bars extending transversely across the chisel and having their cutting edges flush with the cutting edges of the chisel, substantially as described.

2. A mortising tool, comprising a hollow chisel provided at its cutting end with transverse cutters extending across the same and having their cutting edges flush with the cutting edges of the chisel, and bits mounted to revolve in unison and passing through the openings formed by the transverse cutters, substantially as herein shown and described.

3. A mortising tool, comprising the hollow chisel C, having at its lower end transverse

cutters D, the bits F passing through the openings formed by the transverse cutters, the elongated gear wheels G to which the bits are secured, and the pulleys H on the extended shafts of the outermost gear wheels, substantially as herein shown and described. 15
